UNITED STATES PATENT OFFICE.

CHARLES BIRTH, OF KINGSTON BOROUGH, PENNSYLVANIA, ASSIGNOR TO WALES ADDING MACHINE COMPANY, OF WILKES-BARRE, PENNSYLVANIA, A CORPORATION OF PENNSYLVANIA.

CALCULATING-MACHINE.

1,339,542.

Specification of Letters Patent.

Patented May 11, 1920.

Application filed October 7, 1918. Serial No. 257,102.

To all whom it may concern:

Be it known that I, CHARLES BIRTH, a citizen of the United States, residing in the borough of Kingston, Luzerne county, Pennsylvania, have invented new and useful Improvements in Calculating-Machines, of which the following is a specification.

Calculating machines of the prior art, equipped with printing and automatic line spacing mechanisms, have generally been so arranged that the paper will feed or advance at every operation of the machine.

Such automatic operation of the line spacing mechanism is, of course, necessary in listing amounts in vertical columns, to prevent imprinting amounts on top of one another; but as the paper feed mechanism is driven from the main shaft, the paper will also feed at every idle operation of the machine, that is, an operation wherein no printing or accumulation of amounts occurs, as well as on each active operation.

While several advantages have been claimed for the advance of the paper on idle strokes, such as the separation of several successive calculations, for example, to enable the operator to more readily inspect and differentiate the same without confusion, yet the improvement of calculating machines, whereby totals are printed in a color contrasting with that in which the added amounts are printed, together with the designations of such total amounts by signs printed incidentally therewith, has reduced to a minimum the advisability of providing blank spaces of more or less extent to separate successive calculations.

Furthermore, the provision of this wasted space becomes an expense item in offices where considerable listing is performed; and in the interests of economy, this wastage should be eliminated as far as possible.

Since, in the operation of adding machines, it is customary for the operator to actuate the machine several times between the completion of one calculation and the beginning of a succeeding calculation, in order to assure himself that the machine is clear before commencing such succeeding calculation, and further, since it is much easier and more logical to rearrange the performance of the machine, rather than to attempt to reform methods which have become settled habits, of the various adding machine operators throughout the country, I have chosen, as one object of this invention,

to effect an economy in the use of paper, whereby a saving of expense results, without altering in the slightest the methods of operation adopted by any operator of adding and listing machines.

To illustrate, it has been customary to print successive calculations in a vertical column, as follows—

749.82	65
4321.98	
225.61	
5297.41	
43.59	70
892.43	
67.25	
1003.27	75

On some styles of machines, it is customary to head each separate calculation with what is known as a clear sign, which occupies a separate line or space in addition to the lines on which the items are printed, so as to indicate each total by a designating sign printed on the same line therewith.

A modern adding and listing machine, including a sign printing mechanism, if equipped with my invention, would list the foregoing example, as follows—

749.82 C (clear sign)	
4321.98	
225.61	
5297.41 T (total sign and amount)	90
43.59 C (clear sign)	
892.43	
67.25	
1003.27 T (total sign and amount)	95

A comparison of the two lists will at once disclose the saving of space effected.

My invention, however, is applicable in other lines of work involving vertical addition.

The development of the adding machine and the many new uses thereof in relation to bookkeeping methods, has resulted in the provision of special printed forms designed to be inserted about the platen of an adding and listing machine, to receive various data. With such a form, the spacing effected by idly stroking the machine, is not desired, and would be a positive disadvantage, as when the form is designed to accommodate a certain number of items, printed in a desired arrangement.

A style of adding and listing machine known as a ledger posting machine has been devised to handle customers' accounts in banking or other business houses.

5 Such a machine includes a plurality of sets of counters, on one of which sets the debits (as checks drawn by the customer) are accumulated, another set of counters being reserved for the accumulation of credits 10 (as deposits). The total registered on one set is then subtracted from the total on the other set, and the balance printed.

Cards or loose leaf sheets bearing a special 15 printed form, are respectively assigned to each customer, and each time his account is made up, his card is first inserted in the

ledger posting machine, and the amount of his previous balance accumulated on one set of counters and printed. The individual checks drawn by him are accumulated on another set of counters and listed. The deposit or deposits, if any, are accumulated on the first set of counters with the previous balance, and printed, and a subtraction operation effected, to obtain the new balance 25 which may then be printed.

In machines of the prior art designed for this work, it has been customary to arrange the above data on a form, by a method known in the art as "horizontal ledger posting", and which appears in general outline 30 as follows—

Old bal.	Checks	Checks	Checks	Deposits.	New balance.
1234.56	Jul 1	99.81	23.76	84.29	Jul 1 786.80 Jul 1 1526.04
		47.52	53.91	67.32	
		78.27	40.44		
1526.04	Jul 2	101.88	521.36	14.21	Jul 2 921.84 Jul 2 1767.89
		18.74	23.80		

From the above form it will be noted that there is a considerable amount of space 35 wasted, depending upon the number of checks drawn and deposits made each day. In an active account, it is not at all unusual to list twenty or more checks each day, and generally but a single deposit.

40 The Wales type of multiple counter machine, which is fully disclosed in the co-pending application of Pentecost, *et al.* Serial No. 245,273, filed July 17, 1918, when equipped with the invention forming the 45 subject matter of the present application, is enabled to perform vertical ledger posting, upon a form as follows—

John Doe 73 Wood St. Philadelphia, Pa.

50	Jul 1	1234.56	O. B.
		99.81	ck
		47.52	ck
		78.27	ck
		23.76	ck
55		53.91	ck
		40.44	ck
		84.29	ck
		67.32	ck
	Jul 1	786.80	Dep.
60		⊕	
	Jul 1	1526.04	N. B.
	Jul 2	1526.04	O. B.
		101.88	ck
		18.74	ck
65		521.36	ck
		23.80	ck
		14.21	ck
	Jul 2	921.84	Dep.
70		⊕	
	Jul 2	1767.89	N. B.

The above ledger form is retained and

entries made thereon from day to day until it is filled, whereupon it is filed away for reference, and a new card provided for the customer. These cards serve as ledgers, and 75 constitute a permanent record of the transactions between the customer and the business house. It will readily be seen that on forms of this and similar kinds designed to accommodate a certain number of items, unnecessary line spacing would be an inconvenience.

Comparing the vertical ledger posting system with the horizontal posting system, it will be at once evident that the former is 85 the more economical and logical in arrangement, as well as being more readily performed, the amounts following one beneath the other, those designated by the abbreviations "O. B." (old balance); "Dep" (deposit) ⊕ (subtraction sign) and "N. B." (new balance); being printed in a color contrasting with that in which the amounts designated "ck" (check) are printed, to indicate credits. Also the dates are printed by type differing from that in which amounts are printed, to avoid confusion.

Obviously, the particular sequence above outlined, may be varied, the designating 100 abbreviations omitted, or signs substituted, but in any event, the contrasting colors will enable the operator to readily identify the amounts.

Furthermore, a total of the checks may be 105 printed, if desired, beneath the list of individual checks.

In effecting an economy in the use of paper, I contrive to prevent the line space feed of the sheet on idle strokes, without 110

preventing idle stroking of the machine according to the customary operation.

Also, I have arranged to eliminate the advance of the paper in line spacing direction, in clearing operations, which heretofore resulted in the imprint of a sign at the head of the column separately from the succeeding amounts.

The foregoing and other objects will be 10 more fully explained hereinafter and particularly pointed out in the claims.

In the accompanying drawings, Figure 1 is a side view of a Wales multiple counter machine, parts being omitted, equipped 15 with one embodiment of my invention, the machine being in normal idle position;

Fig. 2 is a detail view in side elevation, of 20 my invention, associated with the coacting elements of the machine, the total key being depressed, to render ineffective the line space disabling mechanism;

Fig. 3 is a similar view, showing the clear key depressed;

Fig. 4 is a perspective detail of one element of the train of line space disabling mechanism; and

Fig. 5 is a sectional view of a Wales multiple counter machine, to permit a better comprehension of the operation of the device.

In the Wales multiple counter machine, in connection with which I have chosen to illustrate my invention, a base 968 (Fig. 1) supports side frames 969^a between which 35 are mounted from front to rear, a keyboard or indexing section, an accumulating section; and a printing section, including a platen 2094. It will be understood that my invention is applicable to a single counter 40 machine, as well as to multiple counter machines.

The numeral keys 117 (Fig. 5) of the keyboard or indexing section are arranged in 45 denominational rows, and depression of the keys according to the amount to be accumulated, operates separate levers 116 connected to the individual keys, to project the respective stops 115, correspondingly arranged in denominational rows, into the 50 paths of denominational positioning bars 310.

The stops 115, when projected, displace spring-pressed detents 221, of which there is one for each denominational row of stops, 55 which detents arrest the corresponding positioning bars 310, in case no stops are projected. The positioning bar detents are journaled on a cross shaft 202 extending between the side frames 969^a, and springs 280 60 restore the positioning bar detents to effective position, upon the withdrawal of the projected stops 115.

Front arms 312 journaled on a cross shaft 300, or on a tube 300^b inclosing the cross 65 shaft, and rear arms 311 journaled on a

cross rod 301, pivotally support the several denominational positioning bars 310 for forward and rearward travel.

Control of the positioning bars is effected as follows—

Restoring links 312^d (Fig. 5) connected at their upper ends to offsets 312^m of the respective forward arms 312, are forked at their lower ends to embrace a restraining and restoring bar 294 mounted in levers 220 75 journaled on a cross rod 508^d supported in posts 968^m projecting upwardly from the base 968.

Tensioned springs 383 connect the restoring links 312^d with a slotted guide and 80 anchor plate 220^b fastened to the restraining and restoring bar 294, the forked ends of the restoring links passing through the slots in the anchor plate, for guidance. The slotted anchor plate also preserves the proper 85 spacing between the links.

Swinging arms 323 journaled on the cross shaft 300, or its tube 300^b, carry rolls 340^d entered in cam slots 220^m in the levers 220. Links 214 connect the arms 323 with cranks 90 212 on the main drive shaft 200 journaled in the respective side frames 969^a (Fig. 1). A main restoring spring 285 (Fig. 5) connected to a crank 228 on the main drive shaft, operates to return the parts to, and 95 retain them in, normal idle position, wherein the swinging arms 323 are at the rearward end of their travel, with their rolls 340^d near the rear ends of the slots 220^m, to hold the levers 220 elevated, as shown in 100 Fig. 5. The levers, in turn, retain the restraining and restoring bar 294 in elevated position against the forked ends of the restoring links 312^d which hold the front and rear supporting arms 312, 311, and the positioning bars 310 in their retired positions 105 against the tendency of the drive springs 383 to advance the bars.

Segmental racks or drive members 410, 110 whose stocks 410^m are journaled on a cross shaft 401 intermediate shaft 300 and rod 301, are pivotally connected at 450 to the respective positioning bars 310, and partake of their motion.

A plurality of opposed series of supporting arms 414, each series journaled on its respective cross rod 600, carry parallel axles 400, on which are mounted for independent rotation, the sets of denominational counters 490, 490^x. A pinion 435 is fastened to 115 turn with each counter, and is adapted to engage and disengage with its coacting denominational drive member 410.

As the sets of counters 490, 490^x are similar, a description of one will suffice for both.

The counter pinions 435 are engaged and disengaged relatively to their drive members 410, as follows—

The opposite ends of each axle 400 rest 125 on vertically shiftable supporting plates 130

324, shown best in Fig. 2, located alongside the inner faces of the side frames 969^a, the stems 324^m of which plates are slotted to embrace and be guided by a cross shaft 402. 5 Studs 356 (Fig. 1) projecting outwardly from the respective supporting plates 324, past the outer faces of the adjacent side frames 969^a, pass through supporting arms 322 pivoted at 952^a to the side frames, and 10 counter-disengaging and supporting members or props 319 pivotally connected at their upper ends to the respective supporting arms 322, are slotted at their lower ends at 319^m, to accommodate the opposite ends 15 of a trip bar 303 mounted in and traveling with the swinging arms 323 which control the levers 220. The trip rod 303 travels in an arc, and when the machine is idle, is held at the upper end of its course by the swinging arms 323. In such position, the trip rod, 20 through the props 319, supports the vertically slidable plates 324 at their upper limit of movement, and the plates, in turn, maintain the counter pinions 435 out of mesh 25 with their corresponding segments or drive members 410.

Turning the drive shaft 200 forwardly, against the tension of the main restoring spring 285, draws with it the links 214 to 30 advance the swinging arms 323 and lower the trip rod 303.

The arms 323 cause their rolls 340^a to traverse the cam slots 220^m of the levers 220 to rock the levers and the restraining and 35 restoring bar 294, downwardly, and further tension the drive springs 383. The springs, in turn, pull downwardly the restoring links 312^a to rock the front arms 312 forwardly and advance the positioning bars 310 until 40 they are arrested by the projected stops 115 or by the detents 221 in those denominations wherein no stops have been projected. The continued travel of the levers 220 and bar 294 after the arrest of the positioning bars 45 merely increases the tension on the springs 383.

The positioning bars on their advance, rock the drive racks 410 and the rear supporting arms 311 forwardly.

50 Meanwhile, the trip rod 303 (Fig. 1) has been lowered in an arcuate path to deprive the props or counter-disengaging members 319 of support, but the counters are still held disengaged from the drive members 410 by detaining legs or members 316 pivoted at their upper ends to the studs 356 projecting from the vertically slidable plates 324, and having feet 316^m adapted to seat on rests 958^a swiveled in the side 55 frames. Bridle links 321 pivoted to the respective legs, are slotted, as at 321^m, to accommodate the trip rod 303, which idly traverses the slots in the lower ends of the props 319 and in the bridle links 321 until, 60 near the end of the forward stroke of the 65

main drive shaft, and after the positioning bars 310 and racks or drive members 410 have completed their advance, the rod contacts the end walls of the slots in the bridle links to trip the legs or detaining members 316 off the rests 958^a, whereupon the vertically slidable plates 324 drop, to mesh the pinions 435 on the counters 490, 490^x with the advanced drive members 410. 70

Releasing the main drive shaft at the 75 end of its forward stroke, enables the restoring spring 285 to restore the shaft and connected parts to normal idle position.

The main drive shaft on its return stroke, 80 forces the links 214 rearwardly to restore the swinging arms 323 to their home positions. The arms cause the rolls 340^a to retrace their paths along the cam slots 220^m of the levers 220, to raise the latter and press the restraining and restoring bar 294 85 against the lower ends of the restoring links 312^a. The links 312^a, under the influence of the restraining and restoring bar, retire the positioning bars 310 and drive members 410 to their home positions, and the drive 90 members during such retirement, turn the pinions 435 and counters 490 or 490^x to register thereon an amount corresponding to the numerical values of the depressed keys. 95

At the same time, the trip rod 303 is idly retracing its path and traversing the slots in the bridle links 321 and counter-disengaging members 319, until, near the end of the return stroke, and after the retirement 100 of the racks or drive members 410, the trip rod contacts the upper ends of the slots 319^m in the props 319 to raise the latter and the supporting arms 322 connected thereto, and thereby lift the vertically slidable supporting plates 324, to disengage the counter pinions 435 from the retired drive members 410 and sustain them in such disengaged position. 105

The supporting arms 322, when raised, 110 draw upwardly the detaining members 316 until the feet 316^m clear the seats of the steps 958^a, whereupon springs 385^a snap the legs into place on the seats in readiness for another operation. 115

Suitable carrying mechanism effects the transfer of excess digits from counters of lower denomination to those of next higher denomination.

The printing of the individual items 120 registered on the counters, is accomplished in the following manner.

Links 515 (Fig. 5) connect extensions 311^m of the rear arms 311 with denominational typecarriers 514, the heads of which 125 each carry a vertically arranged series of types 561 corresponding to the values of the keys in their respective rows.

As the rear supporting arms 311 rock forwardly with the front supporting arms on 130

the forward stroke of the main drive shaft 200, they elevate the typecarriers 514 through the above train of connections, to position the proper types 561 at the printing line of the platen 2094, the rear extensions 311^m also releasing trip bars 513 controlling individual latches 511 associated with their respective printing hammers 510, which cooperate with the types. The hammers 510 are further controlled by mechanism common to the Wales type of machine, operated from the main drive shaft, including a universal retaining pawl 518, which pawl, when displaced in normal operations of the machine, releases the hammers to effect the impression of the types on the paper carried by the platen.

On the return stroke of the main drive shaft, the typecarriers 514 are lowered to their home positions, and the printing hammers 510 recocked by the resetting bail 509^a.

It will be remembered that in the adding operation of the machine, as above explained, the counters 490 or 490^x remain disengaged from their drive members or racks 410 until the end of the forward stroke of the main drive shaft, when they engage their racks and remain engaged until the end of the return stroke.

Clearing the counters in readiness for the next calculation, is commonly effected by reversing the direction of rotation of the counters, which operation is readily accomplished by changing the times of engagement and disengagement of the counters and drive members, as follows—

An angular coupler 326^f (Figs. 1, 2 and 3) slidably mounted on the forwardly extending arm of a set lever 317^b fastened to a projecting end of the cross shaft 300, has an upwardly extending arm 326^m, which is notched to accommodate a pin 355^a on the stem of a clearing key 327. A spring 582 holds the coupler effective.

Depression of the clearing key operates through the coupler to rock the set lever 317^b, and the shaft 300, to the opposite end of which is secured a somewhat similar lever (not shown). Links 315 (Fig. 1) connect the upstanding arms of the levers 317^b with the legs or detaining members 316 of the supporting plates 324, and displace the legs relatively to their seats 958^a. At the same time, the upstanding arm of the left hand lever 317^b contacts a stud 359^b on a slide 320 to advance the slide. As the slide advances, a cam slot 320^p formed thereon engages a crank arm 222^d fast on the cross shaft 202, to turn the latter and with it a second similar arm 222^m (Fig. 5), likewise fast on the shaft 202 and connected by a rod 204 with a third arm similar to the arm 222^m, at the opposite side of the machine. The rod 204 extends beneath the series of 60 denominational positioning bar detents 221

and lifts the entire series out of the paths of the positioning bars 310, to enable the latter to travel forwardly.

A lug 216^m (Fig. 1) on a spring-pressed catch 216^d pivoted to a quadrant 211 fast on the main drive shaft, fits over a stud 354^m on the set lever 317^b to lock the latter in depressed position, and thus relieve the operator of the duty of maintaining the clearing key 327 depressed against the tension of its 75 restoring spring 384 and the tension of the set lever restoring spring 382.

Furthermore, an arcuate rib 217 on the quadrant interposes itself over the stud 354^m as the main drive shaft 200 starts on its forward stroke, to continue to maintain the set lever 317^b where adjusted, during the forward stroke of the main drive shaft.

Upon starting to turn the drive shaft 200 forwardly, the vertically sliding supporting plates 324, with the counters 490 or 490^x, descend with the trip rod 303 because the detaining members 316 have been displaced, and the counter pinions 435 engage the drive members 410 before the latter advance from 90 their normal retired positions.

The main drive shaft, as it continues its forward stroke, withdraws the restraining and restoring bar 294 to the opposite end of its throw and tensions the springs 383 to 95 advance the positioning bars 310 and drive members 410, which travel forwardly, and in so doing, turn the engaged counters rearwardly in a reverse direction, until arrested by the contact of cams 411 (Fig. 5) on 100 the respective counters, with lips 612^r formed on the carrying detents 612, and located in the paths of the cams, at which time the counters all register zeros.

The typecarriers 514 rise as the positioning bars 310 and drive members 410 advance under the control of the engaged counters, to locate at the printing line, the types corresponding to the total amount registered on the counters at the beginning of the clearing 110 operation, but since the imprint of this total is not desired, means are provided to prevent the effective operation of the printing hammers, and hence the latter remain inactive.

This printer disabling mechanism is not herein shown, as it forms no part of the present invention, and is fully set forth and claimed in the copending application of Pentecost & Fisher, filed July 17, 1918, Serial No. 245,273, to which reference is made. The counters are disengaged from their advanced drive members 410 prior to the retirement of the latter during the return stroke of the main drive shaft, and as the 125 mechanism for effecting such disengagement is practically duplicated on the opposite side of the machine, a description of that shown on the left side will suffice.

The forwardly projecting arms of coun- 130

ter-disengaging bell crank levers 313 journaled at the opposite ends of the cross rod 301, lie beneath and are arranged to contact studs 357^d on the counter-detaining members or legs 316 to lift the latter, together with the vertically slideable supporting plates 324, and restore the counters to their normal idle position.

Thrust links 314 pivoted to the upwardly extending arms of the bell crank levers 313, extend forwardly and rest upon studs 361 on the counter-disengaging members or props 319, with their free ends extending in advance of the props, to points adjacent to the thrust studs 355 mounted on the set levers 317^b.

Obviously, as the counter-disengaging props 319 are lowered and raised, the free ends of the thrust links move up and down.

Consequently, after the upwardly extending arms of the set levers 317^b which carry the thrust studs 355, rock forwardly in clearing operations, the free ends of the thrust links drop behind the studs when the counter props 319 descend in effecting the engagement of the counter pinions with their drive members.

As the main drive shaft 200 reaches the end of its forward stroke, the locking stud 354^m of the set lever 317^b partially escapes around the rear end of the advanced locking rib 217, due to the tension of the set lever restoring spring 382, but the spring is unable to completely restore the set levers, due to the contact of the thrust studs 355 with the thrust links 314, which contact forces the thrust links part way rearwardly and rocks the bell crank levers 313 to press their forwardly extending arms upwardly against the studs 357^d on the detaining members 316.

The rear end of the locking rib is beveled or inclined, as at 217^m, and at the beginning of the return stroke of the main drive shaft, this beveled end is pressed against the partially released locking stud 354^m and forcibly restores the set levers 317^b to their normal elevated positions, whereby, through the thrust studs 355, thrust links 314 and bell crank levers 313, to lift the counter-detaining members 316, together with the vertically slideable axle-supporting plates 324, and thus disengage the counter pinions 435 from their drive members 410 at the very outset of the return stroke, before the restraining and restoring bar 294 can retire the drive members.

In the event that it is desired to record the total amount on the counters, and retain the amount thereon for further accumulations or other treatment, a total key 327^b is located adjacent the clearing key 327, the total key having a foot 327^b overhanging the forward end of the set lever 317^b. Depression of the total key rocks the set levers in the same manner as explained in connec-

tion with the clearing key, to displace the counter-detaining members 316, and the positioning bar detents 221.

The main drive shaft, on its forward stroke, advances the positioning bars 310 and drive members 410 under control of the engaged counters 490 or 490^x to reversely rotate the counters until the latter are arrested in their zero positions, at which time the typecarriers 514 have positioned types 75 at the printing line corresponding with the total which the counters registered at the beginning of the operation, and the printer-disabling mechanism, remaining idle, the printing hammers are discharged to impress 80 the types against the paper on the platen, just as in listing individual items.

As it is desired in this operation, to retain the total amount on the counters, the disengagement of the counters and their drive members at the beginning of the return stroke is prevented by automatically locking the total key in depressed position, at the end of the forward stroke to prevent the escape of the locking stud 354^m of the set 90 lever from beneath the locking rib 217, in a manner hereinafter set forth and constituting a part of my invention.

Consequently, the counters remain in engagement with their drive members during 95 the return stroke of the main drive shaft, whereby the drive members on their retirement, as explained in connection with the adding operation, turn the counters in adding direction to again cause them to register 100 the total amount in a manner common in the art.

The counters disengage from their drive members at the end of the return stroke in the same manner as in adding operations. 105

Sign printing mechanism may be provided under the control of the clearing and total keys, to print indicia to designate that the machine is clear, and to differentiate the total amount from the list of items, but this 110 mechanism is not shown as it has no direct connection with the present invention. A complete explanation of the sign printing mechanism is included in the copending application of Pentecost and Fisher, filed July 115 17, 1918, Serial No. 245,273.

To enable the operator to select the set of counters on which amounts shall be registered, and to facilitate other functions of the machine, not herein referred to, but explicitly described in the copending application of Pentecost and Fisher, above mentioned, counter-selecting heads 418^m (Fig. 1) having their stems 418 (Fig. 2) fast on a cross shaft 402 extending between the side 125 frames, are located adjacent each vertically slideable supporting plate 324. The selecting heads or members project upwardly between the parallel counter-supporting axles 400 and have open-ended slots 418^r adapted 130

to embrace and confine the axles; when the members are shifted by means of a handle 418^a conveniently secured to one of the heads.

5 Shifting the lever to either extreme of its throw, interposes the heads beneath the opposite ends of one or the other of the axles 400 and withdraws the heads from beneath the remaining axle, whereby such last named 10 axle is solely supported upon the sliding plates 324 to travel up and down therewith during the operation of the machine, as hereinbefore set forth. The first-named axle 400, with its counters, is supported by 15 the heads 418 to maintain the counters out of engagement with their drive members.

By locating the handle 418^a intermediate its extreme positions, the heads 418 extend beneath the opposite ends of all axles, to 20 prevent the engagement of the counters and drive members.

The paper carriage of the machine includes a bracket 2067 having ways 2067^m formed therein, extending across the rear 25 end of the machine and secured to the respective side frames 969^a. A carriage slide 2065 shiftably supported between the ways 2067^m for endwise travel, carries end plates 2010, in which is journaled a platen axle 30 2004 extending between the end plates and supporting the platen 2094.

Line spacing mechanism.

The platen 2094 is rotatable step by step 35 by means of a thrust bar 2026, whose forward end is connected to a cross rod 302 mounted in the swinging arms 323. The thrust bar extends rearwardly and carries a foot 2026^a at its rear end adapted to contact a universal bail 2002 mounted in swinging arms 2016^a fast on stud shafts 2053^b journaled in the opposite end plates 2010 of the traveling carriage.

When the main drive shaft 200 is in its 45 home position, the thrust bar 2026 holds the universal bail in its rearward position against the tension of a drive spring 2486 (Fig. 2).

One arm of a bell crank or operating lever 50 2016 (Figs. 2 and 3) is secured to and projects rearwardly from one of the stub shafts 2053^b, a line space pawl 2014 being pivoted to the bell crank lever and extending upwardly to coact with a ratchet 2020 fixed to 55 turn with the platen.

A spring 2082^a connects the pawl and its operating lever 2016 to cause the tooth of the pawl to engage the ratchet, and a shoulder 2016^m on the operating lever normally 60 contacts a stud 2058^a on the pawl to hold the latter apart from its ratchet when the main drive shaft is in its home position, to enable the platen to be manually rotated in either direction.

65 The main drive shaft 200, on its forward

stroke, advances the swinging arms 323 and withdraws the thrust bar 2026 from the universal bail 2002. The drive spring 2486 (Fig. 2) forces the universal bail to follow the retreating thrust bar, and rocks the arms 70 2016^a and operating lever 2016 to retract the pawl 2014 idly over the ratchet preparatory to taking a new bite thereon.

As the swinging arms 323 restore on the return stroke of the main drive shaft, the 75 thrust bar is forced against the advanced universal bail to return the latter, together with the line space pawl, to normal position, and thereby effect a rotation of the platen to advance the paper to bring a fresh 80 line to the printing point.

The foregoing mechanism is fully shown in prior United States Letters Patent to McFarland, 842,232, January 29, 1907; White, 940,766, November 23, 1909; and in the 85 pending application of Pentecost and Fisher, above referred to, and constitutes a part of my invention only in so far as it is combined to coact with the novel features hereinafter set forth.

As a means to facilitate the entry of amounts in their proper places on forms designed to accommodate a certain arrangement or number of items, without delay, as well as to effect an economy in the use of 90 paper, in calculating machines, I contrive to normally disable the line spacing mechanism, whereby any number of idle strokes or operations may be effected without feeding the paper, whenever it is desired to reset 100 the carrying mechanism before taking a total, or to assure the operator that the machine is cleared, for instance.

Furthermore, I arrange to control such line space disabling mechanism so that it is 105 rendered ineffective upon any operation of the machine whereby amounts are printed.

To these ends, therefore, one embodiment of my invention includes a line space disabling lever or member 524^a pivotally 110 mounted at 564^a, the rear end of which lever normally lies in the path of the universal line space bail 2002 to prevent the latter from following the thrust bar 2026 as the bar is advanced during the forward stroke 115 of the main drive shaft. Consequently, the line space pawl 2014 does not retract for a new bite on the ratchet 2020 and the platen is not turned.

In the particular form in which the invention is herein disclosed, a transmitting lever 329 is conveniently pivoted at 950^m to the left hand side frame 969^a. A spring 339^b connected at one end to a link 329^a, pivoted at its lower end to the forwardly 125 extending arm of the transmitting lever, pulls the link downwardly to normally hold the forward arm of the transmitting lever depressed and the rear arm elevated against the short forwardly projecting finger 329^m 130

of a reversing bail 329^b journaled on a cross rod 903^c. An arm 329^a extending rearwardly from the inner end of the reversing or intermediate bail 329^b, contacts and depresses an extension 524^m of the line space disabling lever 524^a, to hold the disabling lever effective against the tension of a spring 680^m inferior to the spring 389^b.

The intermediate bail 329^b constitutes a convenient medium through which to operate the line space disabling lever, but the bail might readily be omitted, and the transmitting lever 329 arranged to directly operate the line space disabling lever 524^a.

Obviously, since the paper must be line spaced in listing amounts in vertical columns, means must be provided to free the disabling lever 524^a to the action of its spring 680^m which shifts the lever to ineffective position. Therefore, the upper end of the link 329^d is slotted, as at 329^e, to embrace a pin 1857^p on an arm 1814^m fast on a cross shaft 304 journaled in the respective side frames 969^d and extending parallel with and adjacent the rack detent supporting shaft 202. A bail 370 (Fig. 5) carried by the shaft 304 rests upon the offset spring terminal lips 221^m on the positioning bar detents 221 which, it will be remembered, are raised out of the paths of their corresponding positioning bars 310 by the projection of the key-set denominational stops 115, over which the detents extend.

A spring or flexible link 685^m superior to spring 389^b connects the pin 1857^p on the crank 1814^m with the link 329^d to yieldingly hold the bail 370 adjacent the detents 221 or their lips 221^m, and the lower end of the slot 329^e in the link 329^d adjacent the pin 1857^p, as shown in Fig. 1 whereby to permit the latter to shift in the slot independently of the link 329^d.

Depressing a numeral key 117 projects its stop 115 against the lower edge of the detent 221 and forces the latter upwardly against the overlying bail 370 to rock the shaft 304 and the crank 1814^m thereon. The tension of spring 685^m is such that the upward throw of the crank 1814^m is transmitted through the spring without materially changing the position of the pin 1857^p in the slot 329^e in the link 329^d, to raise the latter against the tension of the inferior spring 389^b and swing the forwardly projecting arm of the transmitting lever 329 upwardly, thereby lowering the shorter rear arm thereof from the forwardly projecting finger 329^m of the reversing bail 329^b to relieve the pressure thereagainst. This frees the reversing bail 329^b and the line space disabling lever 524^a to the action of the spring 680^m, which immediately rocks the disabling lever to ineffective position and permits the universal line space bail to advance on the forward stroke of the main drive shaft.

Upon the restoration of the positioning bar stop 115 to idle position, after the universal bail 2002 has returned to normal, the detent 221 returns into the path of its positioning bar 310 and the inferior spring 389^b causes the overlying bail 370 to resume its normal position. The spring 389^b also lowers the link 329^d and depresses the forwardly extending arm of the transmitting lever 329, to rock the reversing bail 329^b and restore the disabling lever 524^a to effective position.

Clearing key control of line space disabling mechanism.

As heretofore explained, depression of the clearing key 327 advances the slide 320 to rock the detent-supporting shaft 202 and the bail 204 extending beneath the several denominational detents 221, to displace the latter out of the paths of their positioning bars 310.

But such action would also lift the overlying bail 370 and effect the displacement of the line space disabling lever 524^a, as set forth in the explanation of the automatic line space disabling mechanism.

In clearing operations, it is desired that no line spacing take place, because no printing occurs, as before explained, and hence, to maintain the line space disabling mechanism effective despite the displacement of the detents 221, I extend the longer forwardly projecting arm of the transmitting lever 329 to a point beneath and in the path of the lower end of the clearing key 327 (Figs. 2 and 3). The extreme end of the transmitting lever may terminate in an upstanding guide 329^s extending alongside the front edge of the clearing key stem 327.

Upon the complete depression of the clearing key, the effect of the positioning bar detents 221 which rock the bail 370 upwardly and turn the shaft 304 and crank 1814^m to raise the link 329^d through the spring 685^m, and render the line space disabling mechanism ineffective, is counteracted by the positive contact of the lower end of the clearing key with the forwardly projecting arm of the transmitting lever 329, which returns the lever to its normal position, and through the reversing bail 329^b, restores the line space disabling arm 524^a to effective position. Such restoration of the lever 329 draws the link 329^d downwardly against the tension of the spring link 685^m, the slot 329^e in the link 329^d permitting relative movement between the link and the pin 1857^p, as shown in Fig. 3.

The clearing key restores to normal during the return stroke of the main drive shaft 200 (as previously explained), prior to the restoration of the positioning bar detents 221, thereby releasing the transmitting lever 329 to the action of the tensioned spring 685^m which then attempts to render

the line space disabling mechanism ineffective, as in adding operations of the machine.

But the displacement of the line space disabling lever 524^a during the return stroke 5 of the main drive shaft, prior to the restoration of the thrust bar 2026 to normal position, would permit the line space bail 2002 to advance until arrested by the thrust bar at some point on its return stroke, and effect 10 at least a partial line space operation.

To prevent such disadvantage, I preferably bevel or undercut the rear end of the line space disabling lever 524^a, so that the pressure exerted by the spring 2486 in forcing 15 the line space bail 2002 against the undercut end of the disabling lever, when the thrust bar 2026 is advanced, will hold the lever 524^a against displacement under the influence of its spring 680^m, until the 20 thrust bar 2026 completes its return travel to relieve the disabling lever 524^a by slightly shifting the line space bail rearwardly.

The slide 320 returns to its normal position at substantially the same time with the 25 clearing key, but owing to the advanced positioning bars 310, the corresponding detents 221 do not restore until the positioning bars have retired, whereupon, the crank 1814^m rocks downwardly and the spring 389^b through the link 329^d, depresses the forward arm of the transmitting lever 329 to hold the line space disabling lever 524^a effective.

The angular coupler 326^f normally connects the set lever 317^b with the clearing key 327. Hence, depression of the set lever by the total key 327^b would draw with it the clearing key and cause the line space disabling mechanism to function.

40 It is desired, in totaling operations, to print the amount and line space the paper, contrary to clearing operations. Therefore, the clearing key 327 through which the printer and line space disabling means are controlled, is disconnected from the set lever 317^b, to which end, a trip lever 327^t (Fig. 2) is pivoted, preferably, on the upper guide stud 950^t of the total key, one arm of which lever extends rearwardly and carries a projection 354^r normally lying directly behind the upwardly extending arm of the angular coupler 326^f. A wiper 352^r projecting from the stem of the totaling key 327^b, enters a cam slot 327^r formed in 45 the remaining arm of the trip lever 327^t. As the total key 327^b is depressed, the wiper 352^r traverses the cam slot to rock the lever 327^t and press the projection 354^r thereon against the adjacent arm 326^m of the 50 coupler 326^f to shift the latter forwardly against the tension of its restoring spring 582 until the recess 326^r of the coupler, clears the pin 355^d on the clearing key 327, whereupon, the set lever 317^b under pressure 55 from the foot 327^p of the total key 327^b,

continues its downward stroke unaccompanied by the clearing key 327, which is held in its normal idle position by its restoring spring 384.

Hence, there is no interference with the 70 printing hammers 510 which operate to print the amount. Likewise, the effect of displacing the rack detents 221, under the influence of the slide 320, to render the line space disabling lever 524^a ineffective, is not 75 counteracted, and the paper is line spaced in the usual manner during the return stroke of the main drive shaft 200.

Furthermore, to prevent the manual depression of the clear key 327 when the total 80 key 327^b is in depressed position, there is a stop lug 327^s on the depending arm of the trip lever 327^t, which lug, when the lever is rocked by the depression of the total key, swings under a stop stud 455 on the clear- 85 ing key, as in Fig. 2.

Depression of the clear key 327 prior to the depression of the total key 327^b, locates the stop stud 455 in the path of the stop lug 327^s to prevent depression of the total 90 key while the clear key is depressed, as in Fig. 3.

A flange 327^t on the total key 327^b operates to guide the key in its travel.

Spring 384^m (Fig. 1) restores the total 95 key to normal elevated position, and the key during its return, causes the wiper 352^r to retrace the cam slot 327^r in the trip lever 327^t, to rock the lever and free the latch 326^f, which, under the influence of its spring 100 582, fits its recess 326^r over the pin 355^d on the clear key stem 327 when the set lever 317^b restores under the influence of its spring 382.

As heretofore explained, depression of 105 the total key 327^b rocks the set lever 317^b and introduces the projection 354^m of the set lever beneath the latch 216^d to hold the lever depressed.

It will be noted however, that there is no 110 normally effective connection between the total key 327^b and the set lever 317^b, and if none was provided, the key would at least partially restore when relieved of pressure.

As it is desirable to maintain the total key in its depressed position, a locking member 325^m (Fig. 1) of irregular contour, is pivoted to the stem of the total key 327^b, at 264^m. The forward edge of the 120 locking member 325^m near its pivot point 264^m is formed into a cam 325^r which normally lies just above the end of a rod 100 protruding from the adjacent side frame. In the present instance, this rod may conveniently be one of the removable rods 125 which holds the keyboard in place, as illustrated, for example, in U. S. patent to Schleicher and Wilgus, No. 1,203,655, November 7, 1916. Also, a shoulder 325^r is 130

formed on the inner edge of the locking member, which shoulder normally lies in a plane below and out of line with an angular stud 963^p projecting laterally from the set lever 317^b. The depending locking member 325^m terminates in a horn 325^s curved to extend rearwardly beneath the spacing pillar 957^d projecting outwardly from the adjacent side frame 969^d. Depression of the total key 327^b carries with it the locking member 325^m, the cam edge 325^p of which wipes along the protruding end of the rod 100 to force the locking member rearwardly so that its shoulder 325^r lies directly beneath the angular stud 963^p on the set lever 317^b, and the latter, descending with the total key owing to the contact of the foot 327^p therewith, and being locked where adjusted by the engagement of the latch 216^d with the projection 354^m on the lever, in turn, holds the total key depressed. The relation of the curve of the horn 325^s to the pillar 957^d is such that the upper concave edge of the horn always lies closely adjacent the pillar.

The main drive shaft 200 on its forward stroke, turns the plate 211 and with it the latch 216^d and the arcuate rib 217, to substitute the latter as a retaining member for the projection 354^m, or lever 317^b, in place of the latch. As the main drive shaft approaches the end of its forward stroke, the rear end of the rib 217 escapes past the stud 354^m which would allow the set lever 317^b and total key 327^b to rise under the influence of their restoring springs 382 and 384^m, as in the clearing operation, to prevent which, the following lock is provided.

A camming latch 325^d journaled at 360^d to the side frame, carries a rearwardly projecting ear 325^t held against the forward edge of the crank 212 by a spring 582^d. At the beginning of the forward stroke, the crank 212 advances and rocks the camming latch 325^d forwardly over a stud 352^d on the depressed total key 327^b, in which position the latch 325^d remains to hold the total key against release at the end of the forward stroke and the beginning of the return stroke. At the beginning of the return stroke of the main drive shaft, the crank retracts and the spring 582^d withdraws the latch 325^d to idle position, but the time necessary to effect the withdrawal of the latch 325^d is sufficient to enable the locking rib 217 to again pass over the projection 354^m to lock the total mechanism in set position. By reason of the locking catch 325^m, the stud 352^d is held in position to be acted upon by the latch 325^d. As the segmental plate 211 approaches the end of its return stroke, it brings the rear face of a yielding rocker 218^b, pivoted at 258^b, against the projection 354^m, contact with which turns 65 the rocker 218^b forwardly to cause it to press

the dog 216^d outwardly away from the adjacent end of the locking rib 217, so as to enable the projection, when it rides off the rib, to escape past the dog, and free the set lever 317^b to the action of its restoring spring 382, which returns the total mechanism to normal position.

A special sign printing mechanism may be associated with the machine, to print signs or abbreviations in connection with the imprint of amounts, but this is well known in the art and requires no description.

Changes may be made in the form and arrangement of the several parts illustrating this embodiment of my invention, without departing from the spirit and scope thereof.

What I claim as new, is:—

1. In a calculating machine, the combination with indexing mechanism; accumulating and printing mechanisms controlled by the indexing mechanism; and line spacing mechanism; of means to normally disable the line spacing mechanism; and means controlled by the indexing mechanism to render the disabling means ineffective.

2. In a calculating machine, the combination with indexing mechanism; accumulating and printing mechanisms controlled by the indexing mechanism; and line spacing mechanism; of means to normally disable the line spacing mechanism, including a shiftable disabling member, normally tending to remain in one of its positions; a transmitting lever to hold the disabling lever in another of its positions; yielding means to shift the transmitting lever to, and hold it in, effective position; and means controlled by the indexing mechanism to render the transmitting lever ineffective.

3. In a calculating machine, the combination with counters; drive members with which the counters are adapted to engage and disengage; indexing mechanism to control the excursions of the drive members; controlling means to vary the duration of engagement of the counters and drive members; printing mechanism; and line space mechanism; of means operable by the indexing mechanism and the controlling means, respectively, to disable the line spacing mechanism.

4. In a calculating machine, the combination with counters; drive members with which the counters are adapted to engage and disengage; indexing mechanism to control the excursions of the drive members; means to vary the times of engagement and disengagement of the counters and drive members, including a set mechanism, independently-operable keys to adjust the set mechanism; printing mechanism, and line space mechanism; of a normally effective line space disabling device; means operable

- by the indexing mechanism, and by the set mechanism, to render the disabling device ineffective; one of the independently-operable keys adapted to positively actuate the disabling device to reestablish the line space disabling device in effective position, notwithstanding the tendency of the set mechanism to retain the disabling means ineffective.
5. In a calculating machine, the combination with counters; drive members with which the counters are adapted to engage and disengage; indexing mechanism to control the excursions of the drive members; means to vary the time and duration of engagement and disengagement of the counters and drive members, including a set mechanism, independently-operable keys to adjust the set mechanism; means to normally connect one of the keys with the set mechanism; printing mechanism; and line space mechanism; of a device to normally disable the line space mechanism; means actuated by the indexing means, and by the set mechanism, to render ineffective the line space disabling means; the independently-operable key which is connected with the set mechanism, adapted to positively reestablish the line space disabling device in effective position, notwithstanding the tendency of the set mechanism to retain the disabling device ineffective; and means actuated by another of the independently-operable keys to disconnect the last-named independently-operable key and the set mechanism.
6. In a calculating machine, the combination with an indexing mechanism; a series of counters, and drive members therefor; the indexing mechanism adapted to control the excursions of the drive members; printing and paper supporting mechanism; line spacing mechanism to advance the paper; and detents for the drive members, displaceable by the indexing mechanism; of a normally effective device to disable the line spacing mechanism; and means controlled by the detents to render ineffective the line space disabling device.
7. In a calculating machine, the combination with counters; drive members therefor, with which the counters are adapted to engage and disengage; indexing mechanism adapted to control the excursions of the drive members; detents for the drive members, displaceable by the indexing mechanism; printing mechanism; and line spacing mechanism; of normally effective means to disable the line spacing mechanism, including a shiftable disabling member; a universal bail operable by any of the detents; and connections between the bail and the disabling member to control the latter.
8. In a calculating machine, the combination with an indexing mechanism; a series of counters, and drive members therefor, the indexing mechanism adapted to control the excursions of the drive members; printing and paper supporting mechanism; line spacing mechanism to advance the paper; independently-operable keys to control the relation between the counters and drive members; and detents for the drive members, actuated by the indexing mechanism, and the independently-operable keys; of a normally effective device to disable the line space mechanism; means controlled by the detents to render the line space disabling means ineffective; one of said independently-operable keys adapted to positively restore the line space disabling means to effective position.
9. In a calculating machine, the combination with an indexing mechanism; a series of counters, and drive members therefor, the indexing mechanism adapted to control the excursions of the drive members; printing and paper supporting mechanism; line spacing mechanism to advance the paper; independently-operable keys to control the relation between the counters and drive members; and detents for the drive members, actuated by the indexing mechanism, and the independently-operable keys; of a normally effective device to disable the line space mechanism; a member common to and operable by any of the detents; a flexible connection between said member and the line space disabling device, to render the device ineffective upon the operation of the indexing mechanism or the independently-operable keys; one of said keys adapted to positively retain the line space disabling device effective.
10. In a calculating machine, the combination with counters; drive members therefor, with which the counters are adapted to engage and disengage; indexing mechanism adapted to control the excursions of the drive members; detents for the drive members, displaceable by the indexing mechanism; printing mechanism; line spacing mechanism; and means to vary the times of engagement and disengagement of the counters and drive members, including a set mechanism also adapted to displace the detents; independently-operable keys to adjust the set mechanism; and means to releasably connect one of the keys and the set mechanism; of means to disable the line spacing mechanism, including a shiftable disabling member, a universal bail controlled by the detents; a train of mechanism between the bail and the disabling member, including a flexible link; one of the independently-operable keys adapted to positively actuate the train of mechanism to render the disabling member effective, notwithstanding the displacement of any of the detents, which normally tends to render the disabling member ineffective; and means

actuated by another of the independently-operable keys to disconnect the first named independently-operable key and the set mechanism, whereby to prevent said key 5 from restoring the disabling member to effective position when the set mechanism is actuated by the second named key.

11. In a calculating machine, the combination with a set of counters, drive members therefor, with which the counters are engageable and disengageable; indexing mechanism to control the excursions of the drive members; printing mechanism; line spacing mechanism; and clearing mechanism for the counters; of disabling means for the line spacing mechanism controlled by the clearing mechanism to prevent operation of the line spacing mechanism.

12. In a calculating machine, the combination with a set of counters, and a set of drive members relatively engageable and disengageable; printing mechanism; line spacing mechanism; totaling and clearing mechanism; independently-operable keys to 25 actuate the totaling and clearing mechanism; and means to releasably connect one of the keys and the totaling and clearing mechanism; of a line space disabling mechanism operable by the last-named key; and means controlled by the other of said keys to disable the releasable connecting means coupling said last-named key and the totaling and clearing mechanism.

13. In a calculating machine, the combination with a set of counters, and a set of drive members relatively engageable and disengageable; indexing mechanism; printing mechanism; line spacing mechanism; totaling and clearing mechanism; independently-operable keys to actuate the totaling and clearing mechanism and means to releasably connect one of the keys and the totaling and clearing mechanism; of a normally effective line space disabling mechanism; yielding means operable by the totaling and clearing mechanism, and by the indexing mechanism, to render the line space disabling mechanism ineffective; the key which is connected with the totaling and clearing mechanism adapted to positively retain the line space disabling mechanism effective, notwithstanding the tendency of the totaling and clearing mechanism to render it ineffective; and means controlled by another of said keys to release the connection between the remaining key and the totaling and clearing mechanism, whereby to enable the latter mechanism to render the line space disabling mechanism ineffective 55 upon the operation of the totaling and clearing mechanism by said other key.

14. In a calculating machine, the combination with a series of counters, and a series of drive members relatively engageable and 60 disengageable; independently-operable keys;

a set mechanism adjustable by said independently-operable keys, to vary the engagement of the counters and drive members; releasable means to normally connect one of the keys and the set mechanism; printing hammers normally effective on each operation of the machine; and line space mechanism; of means to disable the line space mechanism, for instance, said disabling means controlled by that independently-operable key which is connected with the set mechanism; and a tripping means controlled by another of the independently-operable keys, to release the connecting means between the first-mentioned independently-operable key and the set mechanism, to prevent the operation of the disabling means by the first-mentioned independently-operable key when the last-mentioned independently-operable key is actuated to adjust the 85 set mechanism.

15. In a calculating machine, the combination with indexing mechanism; accumulating and printing mechanisms controlled by the indexing mechanism; and line spacing mechanism; of means to normally disable the line spacing mechanism, including a shiftable disabling member, normally tending to remain in one of its positions; a transmitting lever to hold the disabling lever in another of its positions; and means controlled by the indexing mechanism to render the transmitting lever ineffective.

16. In a calculating machine, including printing and line spacing mechanisms, the combination with a series of counters, and a series of drive members, adapted for engagement and disengagement; independently-operable keys; a set mechanism, adjustable by said keys to vary the engagement and disengagement of the counters and drive members; and releasable means to normally connect one of the independently-operable keys and the set mechanism; of a line space disabling mechanism controlled by the last-named key; and means operable by another of the keys to release the connection between the first-named key and the set mechanism when the last-named key is operated, to prevent the operation of the 115 line space disabling mechanism.

17. In a calculating machine, including printing and line spacing mechanisms, the combination with a series of counters, and a series of drive members, adapted for engagement and disengagement; independently-operable keys; a set mechanism, adjustable by said keys to vary the engagement and disengagement of the counters and drive members; and releasable means to normally connect one of the independently-operable keys and the set mechanism; of a line space disabling mechanism controlled by the last-named key; tripping means operable by another of the keys to release the connection 130

between the first-named key and the set mechanism when the last-named key is operated, to prevent the operation of the line space disabling mechanism; and a stop to 5 coact with the tripping means, to prevent depression of either key when the other is in actuated position.

18. In a calculating machine, the combination with a set of counters, and a set 10 of drive members relatively engageable and disengageable; printing and line space mechanisms; totaling and clearing keys; a set mechanism common to both keys; and means to releasably connect one of the keys 15 and the set mechanism; of means controlled by the last-named key, to disable the line space mechanism; and trip means controlled by another of the keys to release the connection between the first-named key and the 20 set mechanism, to prevent actuation of the line space disabling means when the second-named key is operated.

19. In a calculating machine, the combination with a set of counters, and a set of 25 drive members adapted for engagement and disengagement; printing and line spacing mechanisms; totaling and clearing keys; a set mechanism common to both; and a coupler to releasably connect the set mechanism 30 and one of the keys; of means, operable by the clearing key, to prevent effective operation of the line spacing mechanism; and a lever operable by another of the keys, to actuate the coupler and dis- 35 connect the set mechanism and the clearing key, to render the latter ineffective to operate the line space disabling mechanism when the second-named key is operated.

20. In a calculating machine, the combination with a set of counters, and a set of 40 drive members adapted for engagement and disengagement; totaling and clearing keys; a set mechanism common to both; and a coupler to releasably connect the set mechanism 45 and one of the keys; of a controlling lever, one arm of which is adapted to operate the coupler, the opposite arm having a cam slot therein; and a stud shiftable with another of the keys, and entered in the slot 50 to rock the lever.

21. In a calculating machine, the combination with a set of counters; and a set of 55 drive members adapted for engagement and disengagement; mechanism to control the time and duration of engagement of the counters and drive members, including independently-operable keys, each of which actuates said controlling mechanism; and means to releasably connect one of the keys and 60 the mechanism; of means controlled by another of the keys to disconnect the first-named key and the said mechanism, and to prevent operation of the first-named key.

22. In a calculating machine, the combination with a set of counters, and a set of 65 drive

members adapted for engagement and disengagement; mechanism to control the time and duration of engagement of the counters and drive members, including independently-operable keys, each of which actuates 70 said controlling mechanism, and means to releasably connect one of the keys and the mechanism; of means controlled by another of the keys to disconnect the first-named key and the said mechanism, and to prevent 75 operation of the first-named key; said means also adapted to prevent the operation of the second-named key when the first-named key is operated.

23. In a calculating machine, the combination with a set of counters, and a set of 80 drive members adapted for engagement and disengagement; independently-operable total and clearing keys; a set mechanism common to the respective keys; and a 85 coupler to connect the clearing key and the set mechanism; of means operated by the total key, to release the coupler and prevent operation of the clearing key, said means also effective to prevent operation of the 90 total key when the clearing key is in depressed position.

24. In a calculating machine, the combination with a set of counters and a set of 95 drive members adapted for engagement and disengagement; of settable mechanism to control the time and duration of engagement of the counters and drive members, including independently-operable keys, and a set lever common to both; means to releasably 100 connect one of the keys and the set lever; a releasing lever operable by another of said keys to disable the connecting means and free the first-named key from the set lever; a stop carried by the first-named key and 105 adapted to coact with the releasing lever to prevent the depression of either key when the other is in depressed position.

25. In a calculating machine, the combination with a set of counters, and a set of 110 drive members, adapted for engagement and disengagement; of a set mechanism to vary the time and duration of engagement of the counters and drive members, including a key to operate the same; a latch to connect the 115 key and set mechanism against disengagement, when the key is operated; and means to shift the latch into and out of effective position as the key is operated.

26. In a calculating machine, the combination with a set of counters, and a set of 120 drive members, adapted for engagement and disengagement; a set mechanism to vary the time and duration of engagement of the counters and drive members, including a key 125 to operate the same; a latch adapted to travel with the key and having cam faces thereon; an abutment wiped by one of the cam faces during the travel of the key in one direction, to shift the latch to effective 130

position wherein it connects the key and set mechanism; and a second abutment wiped by another of the cam faces during the travel of the key in the opposite direction, 5 to render the latch ineffective.

27. In a calculating machine, the combination with counters; drive members with which the counters are adapted to engage and disengage; indexing mechanism to control the excursions of the drive members; 10 controlling means to vary the duration of engagement of the counters and drive mem-

bers; printing mechanism; and line space mechanism; of a line space disabling member shiftable to effective or ineffective position, and means, operable by the indexing mechanism and the controlling means, respectively, to effect the actuation of the line space disabling member to one of its positions. 15
